United States Patent Office

Des. 175,690
Patented Sept. 27, 1955

175,690

LAMP BASE

Catherine Miller, Antioch, Ill., assignor to The Lawrin
Company, Chicago, Ill., a corporation of Illinois

Application February 7, 1955, Serial No. 34,399

Term of patent 7 years

(Cl. D48—20)

FIG. 1

FIG. 2

Fig. 1 is a front elevational view of a lamp base showing my new design; and

Fig. 2 is a side elevational view thereof.

I claim:

The ornamental design for a lamp base, substantially as shown.
